Atty

UNITED STATES PATENT OFFICE.

JOHN REID, OF NEW YORK, N. Y.

FURNACE-FRONT AIR-VALVE SYSTEM.

1,335,194.

Specification of Letters Patent. Patented Mar. 30, 1920.

Application filed August 7, 1919. Serial No. 315,903.

To all whom it may concern:

Be it known that I, JOHN REID, a subject of the King of Great Britain, and residing at 30 Church street, in the city of New York, in the State of New York, in the United States of America, have invented a new and useful Furnace-Front Air-Valve System, of which the following is the specification.

The invention relates to an air valve system as described in the present specification and illustrated in the accompanying drawings that form part of the same.

The invention consists essentially of the novel placement of valves in the passage for the flow of air from the air supply to the ash pit in the forced draft type of furnace fronts having front and back plates, upper air chamber wall and flare leading to the ash pit.

The objects of the invention are to accommodate the construction of the Reid type of furnace front, in which the fuel passage casing or as more commonly termed the firebox casting is withdrawn in converting the front for liquid fuel purposes, or for repairs or replacements; to further promote the work of standardizing the parts of furnace fronts, particularly for marine work, where quick installations and rapid repairs mean great saving in money by avoiding delays in sailing or *en route*; to insure good seating for the valves and a convenient setting; and generally to provide a valve system that will prove efficient and durable without increasing the cost of production to any material extent if at all.

In the drawings, Figure 1 is a front elevation of the back plate, showing the intermediate parts between the front and back plates, including the valves, in section.

Fig. 2 is a side elevation of the front applied to the mouth of a boiler furnace.

Fig. 3 is a perspective detail of a valve.

Fig. 4 is a detail of the valve shaft and handle.

Fig. 5 is a diagrammatic view, showing the course of the air in a furnace front installation.

Like numerals of reference indicate corresponding parts in each figure.

Referring to the drawings, the numeral 1 indicates the air chamber wall, which is preferably rigidly secured to or forms part with one or the other or both of the plates 2 and 3 forming the front and back plates of a furnace front of the forced draft type.

The wall 1 is above and on either side of the fuel opening in the front plate 2 and the fuel opening in the back plate 3 and at its lower ends is turned inwardly as indicated by the numeral 4, where it meets the fuel passage casing 5, the latter being preferably removable.

The flare 6 leading to the ash pit bridges the space between the plates 2 and 3 at its lower portion following the shape of the plates and at its upper ends is flanged outwardly at 7 and 8 forming immediately below said flanges substantially vertical walls 9 and 10.

The flare 6 is rigidly secured to or forms part with one or the other or both of the plates 2 and 3 and its upper ends are obliquely opposite the angle of the inturned ends 4, thereby forming seats for valves on the vertical portions of the wall 1 and on the vertical portions 9 and 10 of the flare 6.

The valves 11 and 12 are offset at the ends 13 and 14 in opposite curves to meet the vertical portions of the wall 1 and the vertical walls 9 and 10, and are mounted and fixedly secured to the flat portion of the shafts 15 and 16, which are operated by a suitable handle operating device.

The valves 11 and 12 extend obliquely across the passages which are formed by distancing the plates 2 and 3 and which lead from the air supply to the ash pit, and at their upper ends abut the downwardly extending parts of the wall 1 and at their lower ends abut upwardly extending portions of the flare 6.

This invention is particularly adaptable to fronts, where it is essential that the side valves should be out of the way, when any changes are required, such as removing the fuel passage casing in converting the furnace for oil burning or in making repairs, because following the description of the parts in detail, it will readily be seen that the valves remain a permanent fixture quite beyond all operations in introducing apparatus for oil burning and yet are in the very best position to insure efficiency in operation.

Various changes may be made without departing from the spirit of the invention and so long as such changes are within the scope of the claims for novelty following the protection accorded shall not be invalidated.

What I claim is:—
1. In a furnace front having front and back plates provided with alining fuel open-

ings, a removable fuel passage casing seated in the fuel openings therein, an air chamber wall extending from the front plate to the back plate above the fuel openings and 5 having downwardly directed parallel extensions, a flare forming the way to the ash-pit and bridging the space between the front plate and the back plate and having upwardly directed parallel extensions spaced 10 from said first named extensions and from said openings, forming ports between the air chamber walls and the upper portions of the flare, and valves pivotally mounted between the front and back plates between 15 said sets of extensions and at their ends abutting the respective extensions of the air chamber wall and flare to close the aforesaid ports.

2. In a furnace front having front and 20 back plates provided with alining fuel openings, a removable fuel passage casing seated in the fuel openings, said front being formed with air passages to the ash-pit between intermediate parts, and an air chamber wall 25 between said plates partly surrounding said openings and including substantially vertical parallel portions and inturned ends, a flare having upturned ends terminating in vertical parallel walls and with the aforesaid vertical portions of the air chamber 30 wall forming valve seats, and valves journaled in the front and back plates and when closed extending obliquely from the vertical portions of the air chamber wall to the 35 vertical portions of said flare.

3. In a furnace front having front and back plates forming air passages to the ash pit between intermediate parts, said plates having alined fuel openings, an air chamber

wall having downwardly extending portions 40 on either side of the fuel openings in the front and back plates and terminating in inwardly turned extensions to said fuel openings, a removable fuel passage casing introduced into said fuel openings, a flare 45 bridging the way to the ash pit and upwardly turned and flanged at the upper end, said downward extensions of the air chamber wall and upward extensions of the flare forming seats for the valves, and valves 50 mounted on shafts suitably journaled and having oppositely curved offsets at the upper and lower ends formed correspondingly to meet said seats.

4. In a furnace front having front and 55 back plates provided with alining fuel openings therein, said front being formed with air passages to the ash-pit between intermediate parts, a removable fuel passage casing mounted in said fuel openings, an air 60 chamber wall having downwardly extending portions on either side of the fuel openings and terminating in inwardly turned extensions to said fuel openings, a flare bridging the way to the ash-pit and having 65 upwardly extending extensions coöoperating with the downwardly extending portions of the air chamber wall to form valve seats, and valves journaled between the front and back plates and having oppositely turned 70 offsets at their opposite ends for seating against the respective upper ends of the flare and the respective downwardly extending portions of the air chamber wall.

Signed at the city of New York this 17th 75 day of July, 1919.

JOHN REID
